UNITED STATES PATENT OFFICE.

EDWARD S. COBB, OF LOS ANGELES, CALIFORNIA.

RESILIENT MULTIPLE-CONTACT TROLLEY-WHEEL.

SPECIFICATION forming part of Letters Patent No. 737,582, dated September 1, 1903.

Application filed April 14, 1903. Serial No. 152,602. (No model.)

To all whom it may concern:

Be it known that I, EDWARD S. COBB, a citizen of the United States, residing at Los Angeles, in the county of Los Angeles and State 5 of California, have invented a new and useful Resilient Multiple-Contact Trolley-Wheel, of which the following is a specification.

My invention relates to trolley-wheels, and particularly to a trolley-wheel which is adapted 10 for use in high-speed service on electric railways.

Trolley-wheels as commonly constructed have only one point of contact with the wire and are not reliable for service on cars which 15 run at high speeds, being apt to jump from the wire easily when the wire is out of alignment or where the road-bed is uneven or at curves. Such conditions cause excessive sparking and consequent loss of power, the 20 contact of the ordinary trolley under these conditions being ineffectual and not transmitting all the current that it should from the wire.

The object of this invention is to provide a trolley-wheel which will overcome these difficulties. In the present invention the wheel 25 contacts with the wire at several points, and the means for producing the contact is so constructed as to provide an elastic pressure which effectually secures the proper contact 30 of each point. This construction results in easing the shock on the suspension members of the trolley-wire due to the blows incurred by rapid travel of the car, and the elastic construction reduces wear of the overhead structure and gives practically a perfect contact 35 between the trolley-wheel and trolley-wire. Any slight jar or shock of the car tends to jerk the members which suspend the trolley, and the inertia of the suspension members 40 usually throws the ordinary trolley-wheel away from the wire a considerable distance; but with the present invention the trolley-wheel may move bodily toward or from the trolley-wire without necessarily carrying the 45 trolley-wheel out of contact with the wire.

Desirably the trolley is provided with multiple flexible contacts for simultaneous contacting with a wire at a plurality of places on opposite sides thereof, the flexibility of the 50 contacts being sufficient to allow of the passage between them of inequalities of the wire

or of the attachments for suspending the wire in an overhead system.

The main object of such construction is to allow a large portion of the circumference of 55 a trolley-wheel to be flexibly in contact with the wire, thereby affording superior supply of current to the trolley-wheel and making it possible for the axis of the wheel to considerably change its distance from the wire without 60 impairing the effective contact therewith.

Referring to the drawings, Figure I is a side elevation showing the preferred construction of my trolley-wheel. A short length of the trolley-wire is shown with which the 65 wheel is in contact. Figs. II, III, IV, and V are views similar to Fig. I, showing modified constructions. Fig. VI is a section on line VI VI, Fig. I. Fig. VII is a section on line VII VII, Fig. II. Fig. VIII is a section on line 70 VIII VIII, Fig. III. Fig. IX is a section on line IX IX, Fig. IV. Fig. X is a section on line X X, Fig. V.

Referring to the construction illustrated in Fig. I, 1 designates the axle or hub, which 75 may be constructed of a suitable conducting material and may preferably be cast integral with a spider 2. 3 designates the rim of the spider. 4 designates resilient contact-wings which are arranged in opposite pairs around 80 the rim 3, and each pair may be secured to the rim 3 by means of a bolt 5. Each wing is segmental in form and folded over to produce an inner contact-web 6. The inner contact-webs 6 present convex faces which are 85 adapted to squeeze opposite sides of the trolley-wire, and thus maintain the electric connection. The lower ends of the webs 6 terminate a slight distance above the rim 3, and the material of which the wings 4 are composed provides the requisite amount of resiliency to the wings. The space between the inner webs 6 gradually narrows toward the rim 3, and the convex webs converge toward the rim. When the wheel is on the wire, 90 the contact is made laterally through the wire between opposite pairs of wings, as shown in Fig. VI. The resiliency of the web 6 is such that the wheel may have a bodily movement toward and from the wire without causing the 95 wings to be drawn from the wire. Moreover, the pressure between the trolley and the wire 100

is produced directly by the resiliency of the wings and of course indirectly by the upward pressure caused by the upward spring of the trolley-pole.

5 Figs. II and VII show another form of construction in which the wings 8 are formed with both webs extending an equal distance down the opposite faces of the rim 3, the bolt passing through only one web of the wing, 10 which leaves the opposite wing free to spring. As shown in Fig. II, alternate wings have their attaching-bolts passing through the wings on the same side of the rim.

Referring to Fig. III, 9 designates a pair of 15 opposite disks which are formed in "rights" and "lefts." Each disk is provided with segmental wings 10. The space between a pair of wings is similar to the shape of the wing, but is a trifle larger to allow the wings of each 20 disk to project through the slots of the other.

Fig. IV shows wings 11 formed very similar to the webs 6, except that the inner webs are straight and at the bottom are slightly curved just above the rim 12, which in this instance 25 is shown as solid with the hub 1 of the trolley. 13 designates auxiliary blades, segmental in form, which are fastened outside of the wings 11 and serve to stiffen the latter.

Fig. V shows a construction in which the 30 hub 1 carries a grooved rim 14, which is preferably cast integral with the hub and which is deeply grooved. Around the center of the groove is a concentric web 15. 16 designates segmental spring-wings, which are secured to 35 opposite flanges of the rim 14 by means of rivets or other suitable fastening devices which pass through the wings and webs of the rim 14 near the periphery of the same. The wings 16 are curved, so as to present convex

faces which are adapted to bear against the 40 opposite sides of the trolley-wire. When the wheel is held on the wire by the trolley-pole, the web 15 bears against the under side of the wire, while the wings 16 squeeze the wire between them as they bear against the opposite 45 sides of the wire.

There are several specific ways of constructing my trolley-wheel, and in the present application I have shown the construction which seems to be most feasible for accomplishing 50 the desired results.

What I claim, and desire to secure by Letters Patent of the United States, is—

1. A trolley-wheel comprising a rotatable member, and a plurality of segmental spring 55 contact-wings arranged on opposite sides of the member and adapted to contact with both sides of the trolley-wire.

2. A trolley-wheel comprising a rotatable member, and a series of double spring-wings 60 carried thereby and adapted to contact with both sides of the trolley-wire.

3. A trolley having means for contacting with a wire at a plurality of places simultaneously on opposite sides of the wire. 65

4. A trolley having a plurality of flexible contacts for simultaneous contacting with a wire at a plurality of places on opposite sides thereof.

In testimony whereof I have signed my 70 name to this specification, in the presence of two subscribing witnesses, at Los Angeles, in the county of Los Angeles and State of California, this 9th day of April, 1903.

EDWARD S. COBB.
